(57) **CLAIM**

The ornamental design for a powered driver, as shown and described.

DESCRIPTION

FIG. 1 is an environmental perspective view of a powered driver showing my new design.

FIG. 2 is a top left rear perspective view thereof.

FIG. 3 is a left side elevational view thereof.

FIG. 4 is a right side elevational view thereof.

FIG. 5 is a top plan view thereof.

FIG. 6 is a bottom plan view thereof.

FIG. 7 is a front elevational view thereof; and,

FIG. 8 is a rear elevational view thereof.

The broken lines shown in the drawings form no part of the claimed design.
